US00D695722S

(12) **United States Design Patent**
Thompson et al.

(10) **Patent No.:** **US D695,722 S**
(45) **Date of Patent:** **** Dec. 17, 2013**

(54) **EARPHONE**

- (71) Applicants: **AAC Acoustic Technologies (Shenzhen) Co., Ltd.**, Shenzhen (CN); **AAC Technologies Holdings Inc.**, Cayman Islands (GB)
- (72) Inventors: **Roy Alden Thompson**, Dorchester, MA (US); **Kai Chun Yang**, McLean, VA (US)
- (73) Assignees: **AAC Acoustic Technologies (Shenzhen) Co., Ltd.**, Shenzhen (CN); **AAC Technologies Holdings Inc.**, Cayman Islands (GB)

(**) Term: **14 Years**

(21) Appl. No.: **29/437,255**

(22) Filed: **Nov. 14, 2012**

(51) **LOC (9) Cl.** **14-01**

(52) **U.S. Cl.** **D14/223**
USPC **D14/223**

(58) **Field of Classification Search**

USPC D14/223; 181/129, 130, 135; 379/430, 379/431, 420.04; 381/380, 381, 382; 455/90.3, 575.1

(57) **CLAIM**

The ornamental design for an earphone, as shown and described.

DESCRIPTION

FIG. 1 is an isometric view of an earphone showing our new design;

FIG. 2 is front view thereof;

FIG. 3 is a rear view thereof;

FIG. 4 is a left side view thereof;

FIG. 5 is a right side view thereof;

FIG. 6 is a top view thereof; and,

FIG. 7 is bottom view thereof.

The shade lines in the figures show contour and not surface ornamentation.
